CLAIM

The ornamental design for a tool kit and sheath combination for chainsaw, substantially as shown and described.

DESCRIPTION

FIG. 1 is a top plan view of a tool kit and sheath combination for chainsaw showing our new design;

FIG. 2 is a bottom plan view thereof;

FIG. 3 is a right side perspective view thereof; and,

FIG. 4 is a left side perspective view thereof.

The broken lines illustrate portions of the tool kit and sheath combination for chainsaw and form no part of the claimed design.
